(57) **CLAIM**

The ornamental design for a car as shown and described.

DESCRIPTION

FIG. 1 is a front-left-side perspective view of a car according to a first embodiment;

FIG. 2 is a rear-left-side perspective view of the first embodiment;

FIG. 3 is a front view of the first embodiment;

FIG. 4 is a rear view of the first embodiment;

FIG. 5 is a right-side view of the first embodiment;

FIG. 6 is a left-side view of the first embodiment; and

FIG. 7 is a top view of the first embodiment.

FIG. 8 is a front-left-side perspective view of a Car according to a second embodiment;

FIG. 9 is a rear-left-side perspective view of the second embodiment;

FIG. 10 is a front view of the second embodiment;

FIG. 11 is a rear view of the second embodiment;

FIG. 12 is a right-side view of the second embodiment;

FIG. 13 is a left-side view of the second embodiment; and,

FIG. 14 is a top view of the second embodiment.

The broken lines in the drawings illustrate portions of the car that form no part of the claimed design.

1 Claim, 14 Drawing Sheets

(58) Field of Classification Search

CPC B62D 25/00; B62D 25/06; B62D 33/00;
B62D 35/00

See application file for complete search history.
